(57) **CLAIM**

The ornamental designs of a handlebar cover, as shown and described.

DESCRIPTION

FIG. 1 is a top, front, left side, perspective view of a handlebar cover of the new design.

FIG. 2 is a right side elevation view thereof, the left side elevation view being a mirror image.

FIG. 3 is a front elevation view thereof.

FIG. 4 is a top plan view thereof.

FIG. 5 is a rear elevation view thereof.

FIG. 6 is a bottom plan view thereof.
FIG. 7 (additional embodiment) illustrates an alternative top, front, left side, perspective view of the apparatus shown in FIGS. 1-6, but with the longer central aperture being disclaimed.

FIG. 8 is a right side elevation view thereof; the left side elevation view being a mirror image.

FIG. 9 is a front elevation view thereof.

FIG. 10 is a top plan view thereof.

FIG. 11 is a rear elevation view thereof; and,

FIG. 12 is a bottom plan view thereof.

The unevenly dashed broken line showing of a handlebar is for the purpose of illustrating environment which forms no part of the claim. The evenly dashed broken line showing on the handlebar cover in FIGS. 7-12 is for the purpose of defining the claim boundary.
